(57) **CLAIM**

The ornamental design for an outdoor inflatable mattress, as shown and described.

DESCRIPTION

FIG. 1 is a perspective view of an outdoor inflatable mattress showing my new design.

FIG. 2 is a front view thereof.

FIG. 3 is a rear view thereof.

FIG. 4 is a left side view thereof.

FIG. 5 is a right side view thereof.

FIG. 6 is an enlarged top view thereof.

FIG. 7 is an enlarged bottom view thereof.

FIG. 8 is a rear perspective view thereof.

FIG. 9 is an enlarged detail view of area 9 shown in FIG. 1; and,

FIG. 10 is an enlarged detail view of area 10 shown in FIG. 8.

The broken lines in the drawings depict portions of the outdoor inflatable mattress that form no part of the claimed design. The thick evenly spaced broken lines in FIGS. 1, 8, 9, and 10 depict boundary lines of the enlargement views and form no part of the claimed design.

1 Claim, 10 Drawing Sheets
